DEICING MEANS FOR AIRCRAFT

Frederick George Marshall, Leamington Spa, England, assignor to Constant Speed Airscrews Limited, Warwick, England

Application April 28, 1941, Serial No. 390,827
In Great Britain February 27, 1940

5 Claims. (Cl. 244—134)

This invention relates to de-icing means for aircraft having adjustable pitch propellers and has for its object to provide an improved arrangement for controlling the delivery of the de-icing liquid at the required times.

According to the present invention delivery of liquid under pressure for de-icing purposes on aircraft is controlled by adjustment of the pitch angle of the blades of the propeller.

The invention involves the use of one or more valves carried by a part, such as the spinner, which rotates with the propeller.

The valve or each valve may be operated by a cam or projection on a blade of the propeller either directly or indirectly, as by means of a lever.

The de-icing liquid may be supplied to the valve or valves from a container formed in the spinner so that when the valve or valves is or are opened the liquid is delivered under pressure by the centrifugal force created by the rotation of the container. Alternatively, the supply of de-icing liquid may be obtained from a stationary container by means of a pump.

The delivery of the de-icing liquid may be arranged to take place through a plurality of holes in the spinner, said holes being open to the delivery side of the valve or valves.

In the accompanying drawings,

Figure 1 is a longitudinal sectional view through the spinner of an airscrew illustrating one way of carrying out the present invention.

Figure 2 is a plan view thereof, and

Figure 3 is a detail view of the valve and propeller blade.

Referring to the arrangement shown in the drawings, 2 represents one of the blades of an adjustable pitch propeller for aircraft and 3 the usual spinner which encloses the hub of the propeller and rotates therewith.

The nose of the spinner is formed with double walls to provide a container 4 for the de-icing liquid in bulk and is provided with a filling orifice closed by means of a removable plug 5.

A valve 6 which may be of the spring-loaded plunger type, shown more clearly in Figure 3, is fixed to the inside wall of the spinner between the container 4 and a blade 2 of the airscrew and has an inlet connection 7 in open communication with the container and an outlet port 8 communicating with a trough 9 fixed to the inside wall of the spinner below a series of open delivery holes 10 formed in the latter in front of the blade 2.

The outlet port 8 of the valve is normally closed by the valve plunger 11 under the influence of its spring 12 and is arranged to be opened by adjusting the pitch angle of the blade of the propeller. For this purpose the root of the blade

is provided with a clip 13 firmly secured thereto by a bolt 14 and the spinner is fitted with a lever one arm 15 of which is connected with the valve plunger 11 whilst the other arm 16 bears 5 against the head of the bolt 14.

The type of variable pitch propeller employed is one that is controlled from the cockpit and the arrangement is such that when the pilot is aware that ice is forming on the machine he can open the valve for the delivery of de-icing liquid by adjusting the pitch angle of the blades of the propeller from the maximum cruising position, indicated by the dotted centre line a—a in Figure 3, in the direction of the feathering position through an angle of about 5° to the angular position represented in dotted lines in the same figure. This movement is transmitted by the lever to the valve plunger which is thereby caused to uncover the outlet port 8 whereupon de-icing liquid under pressure is sprayed through the holes 10 over the propeller blades and other parts of the aircraft.

I claim:

1. In aircraft the combination with a variable pitch propeller and with a source of supply, of a de-icing liquid of valves for controlling the distribution of said liquid over the machine and means responsive to adjustment of the pitch angle of the blades of said propeller for opening and closing said valves.

2. In aircraft the combination with a variable pitch propeller and with a container for de-icing liquid rotating therewith, of valves for controlling the distribution of said liquid over the machine and means responsive to adjustment of the pitch angle of the blades of said propeller for opening and closing said valves.

3. In aircraft the combination with a variable pitch propeller and with a spinner rotating therewith, of a container for de-icing liquid carried by said spinner and means responsive to adjustment of the blades of said propeller for controlling the distribution of said liquid over the machine.

4. In aircraft the combination with a variable pitch propeller and with a spinner rotating therewith, of a container for de-icing liquid carried by said spinner, valves for controlling the distribution of said liquid over the machine and means responsive to adjustment of the pitch angle of the blades of said propeller for opening and closing said valves.

5. In aircraft the combination with a variable pitch propeller and with a source of supply of de-icing liquid of a valve for controlling the distribution of said liquid over the machine, and a lever responsive to adjustment of the blades of said propeller for opening and closing said valve.

FREDERICK GEORGE MARSHALL.
